WATER RECOVERY UNIT AND METHOD

Glen P. Eidman, Glenn, Eugene L. Begg, Chico, and George F. Hafer, Davis, Calif.

Application November 13, 1956, Serial No. 621,718

8 Claims. (Cl. 47—58)

The present invention is directed to, and it is a major object to provide, a novel device to accumulate and store water for human, wild life, or live stock consumption when—under emergency conditions—a usual or normal source of supply is unavailable; the device functioning to collect the water from the vapors transpired by the green tissues or leaves of living plants.

Another important object of the invention is to provide a water recovery unit which is constructed so that it is of light weight, portable, and foldable into a compact unit so that it can be readily carried in an emergency or survival kit, back pack, saddle bag, or the like.

An additional object of the invention is to provide a water recovery unit which is especially well adapted to be carried and used by military personnel, hunters or other sportsmen, explorers, or any person whose activities may lead into an area where there is a lack of water from a normal source.

A further object of the invention is to provide a water recovery unit which is simple in structure, economical to manufacture, and easy to use; the device including a novel water accumulating bag adapted to enclose, in substantially airtight relation, the green tissues or leaves of a living plant, and—as transpiration occurs—to then cause condensation and recovery of the water from the vapors exhaled from such tissues or leaves.

A still further object of the invention is to provide a practical and reliable water recovery unit, and one which is exceedingly effective for the purpose for which it is designed.

These objects are accomplished by means of such structure and relative arrangement of parts as will fully appear by a perusal of the following specification and claims.

In the drawings:

Fig. 1 is an elevation showing the water recovery unit as in use.

Fig. 2 is a similar but enlarged view, partly in section.

Fig. 3 is a perspective view of the filter unit, detached.

Fig. 4 is a sectional elevation of the filter unit, detached.

Referring now more particularly to the drawings and to the characters of reference marked thereon, the novel, water recovery unit is constructed in the main of flexible moisture-proof material such as plastic, and is also impermeable to air; the unit comprising an elongated preferably cylindrical bag 1 of substantial diameter.

The bag 1 is provided—at the top—with a drawstring 2, while the bottom 3 of such bag is funnel-like and includes a depending central outlet tube 4 normally closed by a pinch-cock clamp 5.

In the lower portion thereof, but some distance above the bottom 3, the bag 1 is fitted internally with a funnel-like false bottom 6 having a depending central neck 7. Such neck 7 communicates—at its lower end—with the apex of the conical top 8 of a cylindrical receptacle 9 whose lower edge is secured to the funnel-like bottom 3 to form therewith an enclosed water storage chamber or reservoir 10.

2

The cylindrical receptacle 9 is of considerably lesser diameter than the bag 1, being disposed symmetrically therein, and prevented from collapse—when the device is in use—by an inverted frusto-conical web 11 which connects between the lower edge of the conical top 8 and the bag 1 in a higher plane.

A cylindrical filter unit, indicated generally at 12, is inserted in the neck 7; such filter unit being shown in detail in Figs. 3 and 4 and comprising the following:

10 The filter unit 12 is made up of a rigid tubular body 13 provided with end plugs 14; one at least being removable. The end plugs 14 are formed with a multiplicity of openings or perforations 15 while the tubular body 13 is filled with activated charcoal 16; there being a circular filter pad 17 between each end plug 14 and the activated charcoal 16 in said body 13.

In use of the above described water recovery unit, the bag 1 is initially open at the top and it is drawn upwardly over a branch 18 of a tree, bush, or other plant 20; this to the end that the green leaves or foliage 20 on such branch hang within the upper portion of said bag. Thereafter, the drawstring 2 is pulled taut and tied, thus closing the top of the bag above the branch 18 so that such bag is then substantially airtight.

25 The bag, of course, depends from the branch 18 not only about the green leaves, or foliage 20, but some distance therebelow in order to dispose the storage chamber or reservoir 10 in a bottom position.

With the clamp 5 in place, and the bag attached to a branch 18, as above described, the temperature inside the bag 1 begins to rise, thus setting up a temperature differential between the atmosphere within the bag and that outside thereof. As transpiration takes place from the green leaves or foliage 20, the relative humidity 30 within said bag increases, and by reason of the temperature differential between the inside and outside of the bag the water from the vapors of transpiration within the bag condenses on the inside surface thereof as small droplets 21. These small water droplets then run downwardly in the bag, passing through the filter unit 12, and thence into the storage chamber or reservoir 10 where a quantity of water builds up, as at 22. The purpose of the filter unit 12, including the activated charcoal 16 and filter pads 17, is to remove any foreign matter, twigs, 35 leaves, or insects, and to filter out any undesirable taste or flavor from the water before it passes into the storage chamber or reservoir 10.

40 After a quantity of water has accumulated in such chamber or reservoir 10 it can be readily drawn off through the outlet tube 4, and for use, merely by manually releasing the clamp 5.

The present invention thus provides a very unique and effective device for obtaining water, by condensation, which is transpired from the green tissues or leaves of 55 growing plants, and under conditions where no other supply of water can be obtained.

From the foregoing description, it will be readily seen that there has been produced such a device, as substantially fulfills the objects of the invention, as set forth 60 herein.

While this specification sets forth in detail the present and preferred construction of the device, still in practice such deviations from such detail may be resorted to as do not form a departure from the spirit of the invention, 65 as defined by the appended claims.

Having thus described the invention, the following is claimed as new and useful, and upon which Letters Patent is desired:

1. A water recovery unit comprising an initially open receptacle arranged to encompass and to depend from green tissue of an exteriorly growing living plant, the receptacle being of a material impermeable to air, means

to close the receptacle in substantially airtight relation about the green tissue, the receptacle being water-tight so as to retain water in a portion thereof below the encompassed green tissue, and normally closed but releasable water outlet means directly communicating with said portion of the receptacle.

2. A water recovery unit, as in claim 1, including a transverse partition in the receptacle above said portion thereof but below the encompassed green tissues, the partition having passage means therethrough in communication with said portion of the receptacle, and a filter unit in said passage means; the filter unit comprising a tubular body, ends closing the body, said ends being perforate, and filter material in the body between the ends.

3. A water recovery unit comprising an elongated initially open-topped bag of flexible material impermeable to air, the bag being adapted to encompass green tissues of a living plant, means to secure the bag at the top in substantially air-tight relation about the adjacent part of the plant, the bag being cylindrical and elongated to depend to a lower end termination below the encompassed green tissues, a funnel-like bottom on the bag, said bottom including a central depending outlet tube, a releasable clamp on the tube, a funnel-like false bottom in the bag between the encompassed green tissues and said first named bottom, the false bottom including a central depending neck, a filter unit in the neck, a cylindrical receptacle of lesser diameter than the bag disposed symmetrically therein below the false bottom, the receptacle having a conical top with which said neck communicates, the lower edge of the receptacle being affixed to said first named bottom whereby the latter forms a bottom closure for said receptacle, and an inverted frusto-conical web secured between the receptacle adjacent the top and the sidewall of the bag in a higher transverse plane.

4. A water recovery unit comprising a receptacle adapted to substantially enclose green tissues of an externally growing living plant, the closure being sufficient to cause a temperature differential between the inside of the receptacle and the surrounding atmosphere, the receptacle being of a flexible material impermeable to air, and means included with the receptacle adapted to collect water condensed from the vapors of transpiration trapped in said receptacle.

5. A water recovery unit comprising a single elongated initially open-topped bag of flexible water-tight material and the upper portion of which forms a receptacle to encompass and to depend from green tissues of an exteriorly growing living plant, means to close the bag in substantially air-tight relation with the plant above said tissue, a false bottom in the bag intermediate the ends thereof, a closed reservoir within the bag below said

false bottom and formed in part with the lower end of the bag, a normally closed outlet from the bottom of the reservoir, a restricted passage-forming neck connecting the false bottom and the reservoir at the top thereof, and a filter unit plugging the neck passage.

6. A structure, as in claim 5, in which said filter unit comprises a tubular body, perforate ends mounted on the body, activated charcoal in the body, and filter pads between the charcoal and said perforate ends.

7. A water recovery unit comprising a single elongated initially open-topped bag of flexible water-tight material and having an upper interior portion arranged to encompass green tissues of an exteriorly growing living plant and to depend therefrom, means to secure the bag at the top above the plant above said tissues in substantially air-tight relation, a reservoir formed with the bag below said portion and communicating directly therewith to collect water condensed from the vapors of transpiration trapped in said upper portion of the bag, and a normally closed outlet passage connected to the bottom of the reservoir.

8. A method of recovering water from the green tissues of a living plant consisting in enclosing such tissues in a water-tight bag in a substantially air-tight manner and so that the lower portion of the bag depends below the enclosed tissues, leaving the bag in place a sufficient length of time for the water vapors transpiring from the tissues and contacting the inner surface of the bag to condense and drain down and collect to a measurable quantity in said lower portion of the bag, and providing for the selective withdrawal for use of such collected water from the bag from below the same.
